(57) **ABSTRACT**

An image forming apparatus includes a plurality of image forming units, a developing voltage power supply, a density detection device, a current detection unit, and a control unit. The plurality of image forming units form an image and substantially same development conditions are set to evenly divide an image density among the image forming units. The control unit detects whether there is an anomaly in a developing device, based on a toner charge amount calculated based on a DC component of developing current when a reference image is formed on an image carrier by each of the developing devices and a density of the reference image. When an anomaly is detected in any of the developing devices, the control unit inhibits use of the image forming unit including the developing device, and resets the development conditions to evenly divide the image density among the usable image forming units.

IMAGE FORMING APPARATUS

INCORPORATION BY REFERENCE

This application is based upon, and claims the benefit of priority from, corresponding Japanese Patent Application No. 2020-027939 filed in the Japan Patent Office on Feb. 21, 2020, the entire contents of which are incorporated herein by reference.

BACKGROUND

Field of the Invention

The present disclosure relates to an image forming apparatus such as a copying machine, a printer, a facsimile machine, and a multifunction device thereof provided with an image carrier, and particularly relates to an image forming apparatus that performs image formation by filling a plurality of developing devices with toner of a same color and a same type.

Description of Related Art

In a typical image forming apparatus using an electro-photographic process, an image forming process is performed in which an electrostatic latent image is formed by irradiating an image carrier such as a photoconductor drum that is uniformly charged by a charging device with laser light from an exposure device, after toner is adhered to the electrostatic latent image by the developing device to form a toner image, the toner image is transferred onto paper (recording medium), and a fixing process is performed.

In such an image forming apparatus, generally, a developing device that develops black toner is mounted in an image forming apparatus for forming a monochromatic image, and developing devices that develop toners of a plurality of colors (for example, yellow, magenta, cyan, and black) are mounted in an image forming apparatus for forming a color image.

SUMMARY

A first configuration according to the present disclosure is directed to an image forming apparatus includes a plurality of image forming units, a developing voltage power supply, a density detection device, a current detection unit, and a control unit. The image forming unit includes an image carrier having a photosensitive layer formed on a surface thereof, and a developing device including a developer carrier that is disposed to face the image carrier and carries a developer containing toner, and configured to form a toner image by adhering the toner to an electrostatic latent image formed on the image carrier, and forms an image by superimposing the toner image of a same color. The control unit controls the image forming units and the developing voltage power supply. The plurality of image forming units use the developer containing the toner of a same color and a same type, and substantially same development conditions are set to evenly divide an image density among the image forming units. The developing voltage power supply applies, to the developer carrier, a developing voltage acquired by superimposing an AC voltage on a DC voltage. The density detection device detects a density of the toner image formed by the developing device. The current detection unit detects a DC component of developing current that flows when the developing voltage is applied to the developer carrier. The

control unit calculates a toner charge amount for each of the developing devices, based on a DC component of the developing current detected by the current detection unit when a reference image is formed on the image carrier by each of the developing devices at a time when an image is not formed, and a density of the reference image detected by the density detection device, and detects whether there is an anomaly in each of the developing devices, based on the calculated toner charge amount. When an anomaly is detected in any of the developing devices, the control unit inhibits use of the image forming unit including the developing device, and resets the development conditions to evenly divide the image density among the usable image forming units.

BRIEF DESCRIPTION OF THE DRAWINGS

FIG. 1 is a side sectional view showing an internal configuration of an image forming apparatus 100 according to one embodiment of the present disclosure;

FIG. 2 is a side sectional view of a developing device 3a mounted in the image forming apparatus 100;

FIG. 3 is a diagram showing a configuration and a control path of an image forming unit Pa;

FIG. 4 is a flowchart showing an example of anomaly detection control of developing devices 3a to 3d in the image forming apparatus 100 according to the present embodiment; and

FIG. 5 is a graph showing a relationship between a printing rate and developing current when reference images having different printing rates are formed.

DETAILED DESCRIPTION

In the following, an embodiment according to the present disclosure is described with reference to the drawings. FIG. 1 is a cross-sectional view showing an internal structure of an image forming apparatus 100 according to one embodiment of the present disclosure. In a main body of the image forming apparatus 100 (herein, a monochromatic printer), four image forming units Pa, Pb, Pc and Pd are disposed in order from an upstream side (left side in FIG. 1) in a transport direction. These image forming units Pa to Pd are provided in association with an image of a same color (black), and a black image is sequentially formed by each step of charging, exposure, development, and transfer.

Photoconductor drums (image carriers) 1a, 1b, 1c and 1d that carry visible images (toner images) of a same color are disposed in these image forming units Pa to Pd, and an intermediary transfer belt (intermediate transfer body) 8 that rotates counterclockwise in FIG. 1 by a belt drive motor (not shown) is provided adjacent to the image forming units Pa to Pd. The toner images formed on the photoconductor drums 1a to 1d are sequentially and primarily transferred and superimposed onto the intermediary transfer belt 8 that moves in contact with each of the photoconductor drums 1a to 1d. Thereafter, the toner images that are primarily transferred onto the intermediary transfer belt 8 are secondarily transferred onto transfer paper P as one example of a recording medium by a secondary transfer roller 9. Further, the transfer paper P on which the toner images are secondarily transferred is discharged from the main body of the image forming apparatus 100 after the toner images are fixed in a fixing unit 13. An image forming process for the photoconductor drums 1a to 1d is performed while rotating the photoconductor drums 1a to 1d clockwise in FIG. 1.

Transfer paper P on which toner images are secondarily transferred is accommodated in a paper cassette 16, which is disposed in a lower part of the main body of the image forming apparatus 100, and is transported to a nip portion between the secondary transfer roller 9 and a driving roller 11 of the intermediary transfer belt 8 via a paper feed roller 12a and a registration roller pair 12b. A sheet made of dielectric resin is used for the intermediary transfer belt 8, and a seamless belt is mainly used. Further, a blade-shaped belt cleaner 19 for removing toner and the like remaining on a surface of the intermediary transfer belt 8 is disposed on a downstream side of the secondary transfer roller 9.

Next, the image forming units Pa to Pd are described. Around and under the rotatably disposed photoconductor drums 1a to 1d, there are provided charging devices 2a, 2b, 2c, and 2d that electrostatically charge the photoconductor drums 1a to 1d, an exposure device 5 that exposes the photoconductor drums 1a to 1d to light of image information, developing devices 3a, 3b, 3c, and 3d that form toner images on the photoconductor drums 1a to 1d, and cleaning devices 7a, 7b, 7c, and 7d that remove a developer (toner) remaining on the photoconductor drums 1a to 1d.

When image data are input from a host device such as a personal computer, first, surfaces of the photoconductor drums 1a to 1d are uniformly charged by the charging devices 2a to 2d. Next, the exposure device 5 irradiates light according to the image data to form an electrostatic latent image according to the image data on the photoconductor drums 1a to 1d. Each of the developing devices 3a to 3d is filled with a specific amount of a two-component developer containing black toner. When a ratio of toner in the two-component developer filled in each of the developing devices 3a to 3d falls below a prescribed value by formation of a toner image to be described later, toner is replenished from toner containers 4a to 4d to the developing devices 3a to 3d. The toner in the developer is supplied onto the photoconductor drums 1a to 1d by the developing devices 3a to 3d, and is electrostatically adhered, whereby a toner image according to the electrostatic latent image formed by exposure from the exposure device 5 is formed.

Then, an electric field is applied between primary transfer rollers 6a to 6d and the photoconductor drums 1a to 1d by the primary transfer rollers 6a to 6d at a specific transfer voltage, and black toner images on the photoconductor drums 1a to 1d are primarily transferred onto the intermediary transfer belt 8. These images are formed with a specific positional relationship that is determined in advance. Thereafter, in preparation for subsequent formation of a new electrostatic latent image, toner and the like remaining on the surfaces of the photoconductor drums 1a to 1d after the primary transfer are removed by the cleaning devices 7a to 7d.

The intermediary transfer belt 8 is stretched between a driven roller 10 on the upstream side, and the driving roller 11 on the downstream side. When the intermediary transfer belt 8 starts to rotate counterclockwise as the driving roller 11 rotates by the belt drive motor (not shown), transfer paper P is transported at a specific timing from a registration roller pair 12b to a nip portion (secondary transfer nip portion) between the driving roller 11 and the secondary transfer roller 9, which is provided adjacent to the driving roller 11, and toner images on the intermediary transfer belt 8 are secondarily transferred onto the transfer paper P. The transfer paper P on which the toner images are secondarily transferred is transported to the fixing unit 13.

The transfer paper P transported to the fixing unit 13 is heated and pressurized by a fixing roller pair 13a to fix the

toner images on a surface of the transfer paper P, and a specific monochromatic image is formed. The transfer paper P on which the monochromatic image is formed has its transport direction determined by branching portions 14 branched in a plurality of directions, and is discharged to a discharge tray 17 by a discharge roller pair 15 as it is (or after the transfer paper P is sent to a double-sided transport path 18, and an image is formed on both surfaces thereof).

Further, an image density sensor 40 is disposed on the 10 downstream side of the image forming unit 1d and at a position facing the intermediary transfer belt 8. As the image density sensor 40, an optical sensor including a light emitting element composed of an LED or the like, and a light receiving element composed of a photodiode or the like is 15 generally used. In measuring an amount of toner adhering to the intermediary transfer belt 8, when measurement light is irradiated from the light emitting element to each of reference images formed on the intermediary transfer belt 8, the measurement light is incident to the light receiving element 20 as light reflected by the toner, and light reflected on the belt surface.

The reflected light from the toner and the belt surface includes specularly reflected light and diffusely reflected light. The specularly reflected light and the diffusely reflected light are separated by a polarization separation prism, and then incident on individual light receiving elements. Each of the light receiving elements photoelectrically converts the received specularly reflected light and diffusely reflected light, and outputs an output signal to a main control unit 80 (see FIG. 3). Then, the toner amount is detected from a characteristic change of the output signals of the specularly reflected light and the diffusely reflected light, and density correction (calibration) is performed by adjusting a characteristic value and the like of a developing voltage in comparison with a reference density that is determined in advance.

FIG. 2 is a side sectional view of the developing device 3a mounted in the image forming apparatus 100. In the following description, the developing device 3a disposed in the image forming unit Pa in FIG. 1 is exemplified. However, since configurations of the developing devices 3b to 3d disposed in the image forming units Pb to Pd are basically similar to the above, description thereof is omitted.

As shown in FIG. 2, the developing device 3a includes a 45 developing container 20 in which a two-component developer (hereinafter, simply referred to as a developer) containing magnetic carrier and toner is stored, and the developing container 20 is divided into a stirring transport chamber 21 and a supply transport chamber 22 by a partition wall 20a. A stirring transport screw 25a and a supply transport screw 25b for mixing toner to be supplied from the toner container 4a (see FIG. 1) with magnetic carrier to stir and charge the toner are respectively and rotatably disposed in the stirring transport chamber 21 and the supply transport chamber 22. In the present embodiment, a two-component developer composed of positively charged toner having an average particle diameter of 6.8 μm , and ferrite/resin coated carrier having an average particle diameter of 35 μm is used, and a toner density (weight ratio of toner to magnetic carrier) is set to 6%.

Then, the developer is transported in the axial direction (direction perpendicular to the plane of FIG. 2) while being stirred by the stirring transport screw 25a and the supply transport screw 25b, and circulates between the stirring transport chamber 21 and the supply transport chamber 22 via an unillustrated developer passage path, which is formed at both ends of the partition wall 20a. Specifically, a circu-

lation path for the developer is formed within the developing container 20 by the stirring transport chamber 21, the supply transport chamber 22, and the developer passage path.

The developing container 20 extends obliquely upward to the right in FIG. 2, and a developing roller 31 is disposed obliquely upward to the right of the supply transport screw 25b within the developing container 20. Then, a part of an outer peripheral surface of the developing roller 31 is exposed through an opening 20b of the developing container 20, and faces the photoconductor drum 1a. The developing roller 31 rotates counterclockwise in FIG. 2. In the present embodiment, a peripheral speed ratio of the developing roller 31 to the photoconductor drum 1a is set to 1.8 (trail rotation at the opposite position), and a distance between the developing roller 31 and the photoconductor drums 1a to 1d is set to 0.30 mm.

The developing roller 31 is constituted of a cylindrical developing sleeve that rotates counterclockwise in FIG. 2, and a magnet (not shown) having a plurality of magnetic poles fixed within the developing sleeve. Although a developing sleeve having a knurled surface is used herein, it is also possible to use a developing sleeve having a large number of concave shapes (dimples) on a surface thereof, a developing sleeve having a blasted surface, and a developing sleeve having a blasted surface or a plated surface in addition to a knurled shape or a concave shape. In the present embodiment, a developing roller 31 having a diameter of 20 mm in which eighty rows of recesses are formed in a circumferential direction by knurling and blasting is used, and a developer transport amount by the developing roller 31 is set to 250 to 300 g/m².

Further, a regulation blade 27 is attached to the developing container 20 along the longitudinal direction of the developing roller 31 (perpendicular to the plane of FIG. 2). A slight clearance (gap) is formed between a tip of the regulation blade 27 and a surface of the developing roller 31. In the present embodiment, a magnetic blade made of stainless steel (SUS430) is used as the regulation blade 27.

A developing voltage including a DC voltage Vdc and an AC voltage Vac is applied to the developing roller 31 by a developing voltage power supply 43 (see FIG. 3). As the development voltage, for example, a voltage acquired by superimposing an AC voltage Vac of a rectangular wave having a frequency of 5 kHz, V_{pp}=1100 V, and Duty=50% on a DC voltage Vdc is used.

FIG. 3 is a diagram showing a configuration and a control path of the image forming unit Pa including the developing device 3a. In the following description, the configuration and the control path of the image forming unit Pa are described. However, since configurations and control paths of the image forming units Pb to Pd are similar to the above, description thereof is omitted.

The developing roller 31 is connected to the developing voltage power supply 43 that generates a vibration voltage in which a DC voltage and an AC voltage are superimposed. The developing voltage power supply 43 includes an AC constant voltage power supply 43a and a DC constant voltage power supply 43b. The AC constant voltage power supply 43a outputs a sinusoidal AC voltage generated from a low-voltage DC voltage, which is pulse-modulated by using a step-up transformer (not shown). The DC constant voltage power supply 43b outputs a DC voltage acquired by rectifying a sinusoidal AC voltage generated from a low-voltage DC voltage, which is pulse-modulated by using a step-up transformer.

The developing voltage power supply 43 outputs a developing voltage acquired by superimposing an AC voltage on

a DC voltage from the AC constant voltage power supply 43a and the DC constant voltage power supply 43b during image formation. A current detection unit 44 detects a value of DC current flowing between the developing roller 31 and the photoconductor drum 1a.

A charging voltage power supply 45 applies, to a charging roller 34 of the charging device 2a, a charging voltage in which an AC voltage is superimposed on a DC voltage. The configuration of the charging voltage power supply 45 is similar to that of the developing voltage power supply 43. A transfer voltage power supply 47 applies a primary transfer voltage and a secondary transfer voltage to the primary transfer rollers 6a to 6d and the secondary transfer roller 9 (see FIG. 1), respectively.

The cleaning device 7a includes a cleaning blade 32 that removes residual toner on the surface of the photoconductor drum 1a, a rubbing roller 33 that removes residual toner on the surface of the photoconductor drum 1a, and rubbing and polishing the surface of the photoconductor drum 1a, and a transport spiral 35 that discharges residual toner removed from the photoconductor drum 1a by the cleaning blade 32 and the rubbing roller 33 to the outside of the cleaning device 7a.

Next, a control system of the image forming apparatus 100 is described with reference to FIG. 3. The image forming apparatus 100 is provided with the main control unit 80 constituted of a CPU and the like. The main control unit 80 is connected to a storage unit 70 including a ROM, a RAM, and the like. The main control unit 80 controls, based on a control program and control data stored in the storage unit 70, each unit of the image forming apparatus 100 (charging devices 2a to 2d, developing devices 3a to 3d, exposure device 5, primary transfer rollers 6a to 6d, cleaning devices 7a to 7d, secondary transfer roller 9, fixing unit 13, developing voltage power supply 43, current detection unit 44, charging voltage power supply 45, transfer voltage power supply 47, voltage control unit 50, drive control unit 51, and the like).

The voltage control unit 50 controls the developing voltage power supply 43 that applies a developing voltage to the developing roller 31, the charging voltage power supply 45 that applies a charging voltage to the charging roller 34, and the transfer voltage power supply 47 that applies a transfer voltage to the primary transfer rollers 6a to 6d and the secondary transfer roller 9. The drive control unit 51 controls a main motor 53 that rotationally drives the photoconductor drums 1a to 1d. The voltage control unit 50 and the drive control unit 51 may be constituted of a control program stored in the storage unit 70.

A liquid crystal display unit 90 and a transmission/reception unit 91 are connected to the main control unit 80. The liquid crystal display unit 90 functions as a touch panel for the user to perform various settings of the image forming apparatus 100, and displays a state of the image forming apparatus 100, an image forming status, the number of prints, and the like. The transmission/reception unit 91 communicates with the outside by using a telephone line or an Internet line.

The image forming apparatus 100 according to the present embodiment is provided with four developing devices 3a to 3d filled with toner of a same color, and developing is performed by distributing an amount of toner necessary for forming an image at a target density for each of the developing devices 3a to 3d. Specifically, when only A is necessary as a toner development amount for forming an image at a target density, and developing is performed by using the four developing devices 3a to 3d, developing is performed

by distributing the toner development amount by A/4 for each of the developing devices **3a** to **3d**.

A developing method including a plurality of (herein, four) developing devices **3a** to **3d** filled with toner of a same color and a same type is advantageous when a frequency with which an image having a high printing rate is continued is high. When the printing rate is high, a difference in the image density is likely to occur in the axial direction of the developing roller **31**. As a result, it becomes difficult to reproduce uniformity with only one developing device. In view of the above, by superimposing a halftone image by the plurality of developing devices **3a** to **3d**, uniformity can be reproduced. Further, in some cases, by setting a transport direction of a developer in stirring sections of two of the four developing devices **3a** to **3d** (for example, the developing devices **3b** and **3d**) in the opposite direction, image uniformity in the axial direction of the developing roller **31** can be further improved.

As described above, in a method of forming an image by superimposing a toner image of a same color a plurality of times, when an anomaly occurs in any of the developing devices **3a** to **3d**, it is preferable to form an image by stopping use of the image forming units **Pa** to **Pd** including the anomalous developing devices **3a** to **3d**, and using the other image forming units **Pa** to **Pd**. In addition, the anomaly may be recovered by causing the anomalous developing devices **3a** to **3d** to perform an aging operation or a forcible ejection operation of toner while the anomalous developing devices **3a** to **3d** are kept in a stopped state or are not in use. In this case, it is necessary to resume the image forming units **Pa** to **Pd** in an unused state.

In order to determine stopping or resuming the image forming units **Pa** to **Pd** as described above, it is necessary to detect in which one of the developing devices **3a** to **3d**, an anomaly has occurred, or an anomaly has been resolved. However, when image formation is performed by using the image forming units **Pa** to **Pd** including the developing devices **3a** to **3d** filled with toner of a same color, occurrence of an anomaly or recovery of the developing devices **3a** to **3d** cannot be easily detected.

In view of the above, in the image forming apparatus **100** according to the present embodiment, a DC component of developing current flowing between the developing rollers **31** of the developing devices **3a** to **3d** and the photoconductor drums **1a** to **1d** during image formation, and a toner development amount are measured, and anomalous developing devices **3a** to **3d** are detected based on a toner charge amount to be calculated from the developing current and the toner development amount. In the following, a method of detecting anomalous developing devices **3a** to **3d** is described.

FIG. 4 is a flowchart showing an example of anomaly detection control of the developing devices **3a** to **3d** in the image forming apparatus **100** according to the present disclosure. An anomaly detection procedure of the developing devices **3a** to **3d** is described in detail along the steps in FIG. 4 with reference to FIGS. 1 to 3, and FIG. 5 to be described later as necessary.

First, the main control unit **80** determines whether a print command is received (step S1). When the print command is received (Yes in step S1), development conditions are set to divide an image density among the operable image forming units **Pa** to **Pd** (step S2). Since all of the four image forming units **Pa** to **Pd** are normal at an initial stage of use of the image forming apparatus **100**, development conditions (de-

velopment potential difference V_{dc-VL}) of each of the developing devices **3a** to **3d** are set to divide the image density into four equal parts.

For example, when a target density (ID; image density)=0.8, the development potential difference V_{dc-VL} necessary for dividing the target density into four equal parts (ID=0.2) is set. In the present embodiment, when all the four image forming units **Pa** to **Pd** are used, a DC voltage $V_{dc}=250V$ of a developing voltage and a surface potential $V_0=350V$ are set.

Next, the main control unit **80** determines whether it is a timing for calculating a toner charge amount (step S3). The estimated timing for the toner charge amount may be, for example, when the image forming apparatus **100** returns from a power saving (sleep) mode, or when a cumulative number of prints based on previous calculation of the toner charge amount is equal to or more than a specific number at the end of a printing operation. When it is a timing for calculating the toner charge amount (Yes in step S3), a toner charge amount **Q** within each of the developing devices **3a** to **3d** is calculated (step S4).

Specifically, after the surfaces of the photoconductor drums **1a** to **1d** are charged by the charging devices **2a** to **2d**, an electrostatic latent image having a pattern for charge amount measurement is formed on the photoconductor drums **1a** to **1d** by the exposure device **5**. Then, a developing voltage for measurement is applied to the developing roller **31** by the developing voltage power supply **43** to develop the electrostatic latent image into a toner image, thereby forming the charge amount measurement pattern on the photoconductor drums **1a** to **1d**. At the same time, the current detection unit **44** detects a DC component of developing current flowing through the developing roller **31** during formation of the charge amount measurement pattern.

The charge amount measurement pattern is a rectangular pattern in which the axial dimensions of the photoconductor drums **1a** to **1d** cover the entirety of an exposure width, and the circumferential dimensions thereof are equal to or longer than the peripheral length (one turn) of the developing roller **31**. A potential of the electrostatic latent image (potential after exposure) having the charge amount measurement pattern is set to 250V, and development is performed by applying, to the developing roller **31**, a developing voltage for measurement in which an AC voltage of 1100V and a duty of 50% is superimposed on a DC voltage of 350V.

When a charge amount measurement pattern is formed, the developing roller **31** is rotated by one or more turns in a state where a reference developing voltage including a reference DC voltage and a reference AC voltage is applied, and then the reference developing voltage is switched to a developing voltage for measurement. The developing voltage for measurement is acquired by changing only a DC voltage from a reference DC voltage while keeping an AC voltage as a reference AC voltage. The reference developing voltage is applied first so as not to be affected by a previous development history. Generally, the reference developing voltage uses voltage conditions for use in printing. If the reference developing voltage is only composed of a DC voltage, the effect of eliminating the development history is weak. Therefore, it is preferable to superimpose an AC voltage on a DC voltage.

Next, a specific primary transfer voltage is applied to the primary transfer rollers **6a** to **6d** to transfer the charge amount measurement pattern onto the intermediary transfer belt **8**. Then, the image density sensor **40** detects the density of the charge amount measurement pattern.

When formation of the charge amount measurement pattern is finished, the reference developing voltage is applied to the developing roller 31 again. When the developing roller 31 makes one or more turns, the developing voltage for measurement is applied again, and the image density and the developing current are measured in a similar manner. The above operation is repeated a plurality of times to acquire a relationship between a printing rate and developing current.

FIG. 5 is a graph showing a relationship between a printing rate and developing current when charge amount measurement patterns having different printing rates are formed. In actual calculation, it is necessary to calculate a current amount [$\mu\text{A}/\text{cm}^2$] per unit area by dividing developing current by a measured area. By converting a printing rate into a toner development amount on the horizontal axis of the graph shown in FIG. 5, based on a detected density of a charge amount measurement pattern, an approximate straight line showing a relationship between a toner development amount and developing current is acquired. The toner charge amount Q is calculated from a gradient of the approximate straight line.

When the image density of the charge amount measurement pattern is changed, it is preferable to expose the entire surfaces of the photoconductor drums 1a to 1d by the exposure device 5, and change V_0 and V_{dc} , while keeping the potential difference V_0-V_{dc} between the surface potential (non-exposed portion potential) of the photoconductor drums 1a to 1d, and the DC component V_{dc} of the developing voltage for measurement to be applied to the developing roller 31 constant.

Thus, it is possible to suppress carrier development at an end portion (edge portion) of the charge amount measurement pattern. Further, when a dot-shaped image is formed by changing the printing rate, a high density portion is generated in a dot peripheral portion. However, since the high density portion of the dot peripheral portion disappears by exposing the entire surfaces by the exposure device 5, it is possible to reduce an error when the density of the charge amount measurement pattern is converted into the toner development amount.

The method of measuring the toner charge amount is not limited to the above-mentioned method. For example, it is also possible to use a method of measuring a toner charge amount, based on a relationship between a frequency when an electrostatic latent image having a same charge amount measurement pattern is developed by changing a frequency of an AC component of a developing voltage, and developing current flowing during formation of a reference image.

Returning to FIG. 4, the main control unit 80 determines whether the toner charge amount Q within each of the developing devices 3a to 3d calculated in step S4 is $Q_1 < Q < Q_2$ in all the developing devices 3a to 3d (step S5). Q_1 and Q_2 are a lower limit value and an upper limit value of the toner charge amount Q , respectively. In the present embodiment, a central value (target value) of the toner charge amount is set to 25 $\mu\text{C}/\text{g}$, the lower limit value Q_1 is set to $\frac{1}{2}$ (=12.5 $\mu\text{C}/\text{g}$) of the target value, and the upper limit value Q_2 is set to two times (=50 $\mu\text{C}/\text{g}$) of the target value h .

When the toner charge amount is Q_1 (12.5 $\mu\text{C}/\text{g}$) or less, it is conceived that the toner charge amount of the developing devices 3a to 3d in which deteriorated toner is used due to a poor storage condition has decreased. When the toner charge amount is Q_2 (50 $\mu\text{C}/\text{g}$) or more, it is conceived that the toner charge amount of the developing devices 3a to 3d in which new toner that is not deteriorated is used has

increased. The main control unit 80 determines that the image forming units Pa to Pd including the developing devices 3a to 3d that do not satisfy $Q_1 < Q < Q_2$ are anomalous.

When $Q_1 < Q < Q_2$ is not satisfied in any of the developing devices 3a to 3d (No in step S5), the main control unit 80 determines whether there is an anomaly in three or more of the developing devices 3a to 3d (step S6). When there is an anomaly in two or less of the developing devices 3a to 3d (No in step S6), the main control unit 80 inhibits use of the image forming units Pa to Pd including the developing devices 3a to 3d in which $Q \leq Q_1$ or $Q \geq Q_2$ (Step S7).

Next, the main control unit 80 sets development conditions to divide an image density among the image forming units Pa to Pd that are operable at a present time (step S8). For example, when the target density ID (image density)=0.8, and the toner charge amount Q within the developing device 3a is $Q \leq Q_1$ or $Q \geq Q_2$, the main control unit 80 inhibits use of the image forming unit Pa, and changes each of the target densities to $ID=0.27$ to divide the image density into three equal parts among the remaining image forming units Pb to Pd. Then, the main control unit 80 resets the development conditions of the developing devices 3b to 3d. The resetting method includes a method of changing the development potential difference $V_{dc}-VL$ required to set $ID=0.27$ by calculation, and a method of performing calibration to reset $V_{dc}-VL$. In the present embodiment, when three of the developing devices 3a to 3d are used, a DC voltage $V_{dc}=300\text{V}$ of a developing voltage, and a surface potential $V_0=400\text{V}$ are set.

On the other hand, in step S5, when $Q_1 < Q < Q_2$ in all the developing devices 3a to 3d (Yes in step S5), the main control unit 80 sets the development conditions to divide the image density into four equal parts among the four operable image forming units Pa to Pd (step S8).

For example, when the development conditions of the image forming units Pa to Pd are set to divide the image density into four equal parts in advance in step S2, it is not necessary to reset the development conditions. When it is determined that there is an anomaly in the image forming unit Pa in a previous printing operation, and the development conditions of each of the image forming units Pb to Pd are set to divide the image density into three equal parts, the development potential difference $V_{dc}-VL$, which is necessary for dividing the image density into four equal parts among the four image forming units Pa to Pd including the image forming unit Pa that becomes unable by a recovery operation, is changed by calculation, or calibration is performed by changing the target density to reset $V_{dc}-VL$. Then, printing is performed under the development conditions set in step S8 (step S9).

Thereafter, when there are unusable image forming units Pa to Pd, the main control unit 80 performs a recovery operation of the image forming units Pa to Pd (step S10). For example, when the image forming unit Pa is unusable, it is presumed that the toner charge amount of the developing device 3a is larger (or smaller) than that of the other developing devices 3b to 3d for some reason. Depending on a reason of change in the toner charge amount, it is possible to classify causes into those that are resolved by performing a specific recovery operation, and those that cannot be resolved even when a recovery operation is performed.

In view of the above, by performing a recovery operation according to a change in the toner charge amount, and calculating the toner charge amount at a next timing for calculating the toner charge amount, it is possible to deter-

11

mine whether the image forming unit P_a that is determined to be anomalous is recovered.

As a specific example of the recovery operation, when the toner charge amount is lower (or higher) than a certain value, specifically, when the toner charge amount is out of a specific range, an electrostatic latent image pattern (solid pattern) is formed on the photoconductor drums $1a$ to $1d$, and a developing voltage is applied to the developing roller 31 to move (forcibly eject) toner on the developing roller 31 onto the photoconductor drums $1a$ to $1d$. Thereafter, new toner is replenished from the toner containers $4a$ to $4d$.

Further, when the toner charge amount is low, it is also effective to use a method of increasing the toner charge amount by lengthening the aging (stirring) time of a developer within the developing devices $3a$ to $3d$. When the toner charge amount is higher than a certain level, it is also effective to use a method in which the developing devices $3a$ to $3d$ are kept stationary for a certain period of time to stabilize the toner charge amount. These recovery operations can be selected according to properties of toner for use.

Then, when the toner charge amount Q satisfies $Q_1 < Q < Q_2$ by the recovery operation, the development conditions are reset again together with the other image forming units P_b to P_d . When recovery is not possible even after the recovery operation is performed, the liquid crystal display unit 90 is notified to urge replacement of the developing device $3a$, since it is necessary to replace the developing device $3a$. Further, when it is determined that there is an anomaly in the image forming unit P_a , the replacement operation may be performed without performing the recovery operation.

Further, when there is an anomaly in three or more of the developing devices $3a$ to $3d$ (for example, developing devices $3a$ to $3c$) in step S_6 (Yes in step S_6), an operable image forming unit among the image forming units P_a to P_d is only one (image forming unit P_d). In this case, since image quality cannot be guaranteed, printing is stopped (step S_{11}). Then, a warning is displayed on the liquid crystal display unit 90 (step S_{12}), a recovery operation of the developing devices $3a$ to $3d$ that are determined to be anomalous is performed (step S_{10}), and the process is finished.

When it is not the timing for calculating the toner charge amount in step S_3 (No in step S_3), printing is performed under the development conditions set in step S_2 without calculating a toner charge amount and detecting an anomaly in the developing devices $3a$ to $3d$ (Step S_{13}), and the process is finished.

According to the control example shown in FIG. 4, in the image forming apparatus 100 in which the developing devices $3a$ to $3d$ are filled with toner of a same color and a same type to form an image, it is possible to easily and accurately detect an anomaly in the developing devices $3a$ to $3d$ by using the toner charge amount Q within the developing devices $3a$ to $3d$, which is calculated based on a relationship between developing current flowing when a charge amount measurement pattern is formed, and a toner development amount to be calculated from an image density of the charge amount measurement pattern.

Then, by determining whether the image forming units P_a to P_d including the developing devices $3a$ to $3d$ are usable based on a detection result, and setting development conditions of the developing devices $3a$ to $3d$ of the usable image forming units P_a to P_d , it is possible to advantageously suppress image defects such as development ghost, image fog, and a transfer failure resulting from a change in the toner charge amount.

12

In addition, by performing a recovery operation for the developing devices $3a$ to $3d$, which are determined to be anomalous, it is possible to restore the image forming units P_a to P_d to a usable state. Thus, there is no likelihood that the recoverable developing devices $3a$ to $3d$ may be replaced, and it is possible to reduce the running cost of the image forming apparatus 100 .

In the control example shown in FIG. 4, the recovery operation of the developing devices $3a$ to $3d$ that are determined to be anomalous is performed after printing is finished. However, a timing for performing the recovery operation is not limited to the above. For example, the recovery operation may be performed between sheets of paper being printed. Alternatively, a dedicated recovery mode may be provided, and the recovery mode may be performed at any timing by input from the liquid crystal display unit 90 or a personal computer.

Further, in the above control example, the recovery operation is performed for the developing devices $3a$ to $3d$ in which $Q \leq Q_1$ or $Q \geq Q_2$. However, as far as the toner charge amount is higher (or lower) than a certain level, even when $Q_1 < Q < Q_2$ is satisfied, the recovery operation may be performed. For example, when the toner charge amount is Q_1' (20 $\mu\text{C/g}$) or less, and Q_2' (40 $\mu\text{C/g}$) or more, a forcible ejection operation may be performed between sheets of paper being printing or after printing is finished, or a recovery operation such as lengthening the aging (stirring) time may be performed.

Others features of the present disclosure are not limited to the above embodiment, and various changes are available without departing from the spirit of the present disclosure. For example, in the above embodiment, the lower limit value Q_1 and the upper limit value Q_2 of the toner charge amount are set, and it is determined whether there is an anomaly in the developing devices $3a$ to $3d$ by determining whether the calculated toner charge amount Q satisfies $Q_1 < Q < Q_2$. However, for example, it is also possible to determine whether there is an anomaly in the developing devices $3a$ to $3d$ in a deviated state from a calculated average value of toner charge amounts of the developing devices $3a$ to $3d$.

However, when determination is made based on a deviated state from an average value of toner charge amounts, if an anomaly occurs in the toner charge amount in two or more of the developing devices $3a$ to $3d$ at the same time, a normal value may be deviated from the average value. In view of the above, it is preferable to determine whether there is an anomaly in the developing devices $3a$ to $3d$, based on determination as to whether the toner charge amount Q lies within a range from the lower limit value Q_1 to the upper limit value Q_2 , as described above in the embodiment.

Further, in the above embodiment, the image forming apparatus 100 has been described by taking, as an example, a monochromatic printer in which the developing devices $3a$ to $3d$ are filled with black toner as shown in FIG. 1. However, the image forming apparatus 100 is not limited to a monochromatic printer and a monochromatic copying machine, and may be a color copying machine or a color printer provided with a plurality of developing devices for each color.

The present disclosure is applicable to an image forming apparatus that forms an image by filling a plurality of developing devices with toner of a same color and a same type. By using the present disclosure, it is possible to provide an image forming apparatus capable of easily and accurately detecting an image forming unit including a

13

developing device in which an anomaly has occurred, and advantageously suppressing occurrence of image defects.

What is claimed is:

1. An image forming apparatus comprising:
a plurality of image forming units each of which includes
an image carrier having a photosensitive layer formed
on a surface thereof, and
a developing device including a developer carrier that
is disposed to face the image carrier and carries a
developer containing toner, and configured to form a
toner image by adhering the toner to an electrostatic
latent image formed on the image carrier, and forms
an image by superimposing the toner image of a
same color;
a developing voltage power supply that applies, to the
developer carrier, a developing voltage acquired by
superimposing an AC voltage on a DC voltage;
a density detection device that detects a density of the
toner image formed by the developing device;
a current detection unit that detects a DC component of
developing current that flows when the developing
voltage is applied to the developer carrier; and
a control unit that controls the image forming units and
the developing voltage power supply, wherein
the plurality of image forming units use the developer
containing the toner of a same color and a same type,
and substantially same development conditions are set
to evenly divide an image density among the image
forming units,
the control unit calculates a toner charge amount for each
of the developing devices, based on a DC component of
the developing current detected by the current detection
unit when a reference image is formed on the image
carrier by each of the developing devices at a time
when an image is not formed, and a density of the
reference image detected by the density detection
device, and detects whether there is an anomaly in each
of the developing devices, based on the calculated toner
charge amount, and
when an anomaly is detected in any of the developing
devices, the control unit inhibits use of the image
forming unit including the developing device, and
resets the development conditions to evenly divide the
image density among the usable image forming units.

14

2. The image forming apparatus according to claim 1,
wherein
the control unit inhibits use of the image forming unit
including the developing device, when the toner charge
amount Q within the developing device is equal to or
lower than a lower limit value $Q1$ or is equal to or
higher than an upper limit value $Q2$.
3. The image forming apparatus according to claim 1,
wherein
the control unit inhibits use of the image forming unit
including the developing device, when the toner charge
amount Q within the developing device is deviated
from an average value of the toner charge amounts
within all the developing devices by a certain value or
more.
4. The image forming apparatus according to claim 1,
wherein
the control unit performs a recovery operation of recov-
ering the toner charge amount of the developing device
in which an anomaly is detected.
5. The image forming apparatus according to claim 4,
wherein
the control unit performs, as the recovery operation, a
forceful ejection operation of ejecting the toner within
the developing device onto the image carrier.
6. The image forming apparatus according to claim 4,
wherein
the control unit resets the development conditions to
evenly divide the image density among all the usable
image forming units including the developing device,
when the toner charge amount of the developing device
in which an anomaly is detected is recovered by the
recovery operation.
7. The image forming apparatus according to claim 4,
further comprising a notification device that notifies a state
of the image forming unit, wherein
the control unit causes the notification unit to notify to
urge replacement of the developing device, when the
toner charge amount of the developing device is not
recovered after the recovery operation is performed.
8. The image forming apparatus according to claim 1,
further comprising three or more of the image forming units,
wherein
the control unit stops an image forming operation, when
the number of usable image forming units is one or less.
